BATHING UNIT

Franklin Ponder, 2915 Fulton St., Berkeley, Calif.

Filed Aug. 27, 1963, Ser. No. 76,363

Term of patent 14 years

(Cl. D4—4)

FIG. 1

FIG. 2

FIGURE 2 is a perspective view similar to that of FIGURE 1 with the front wall and one of the end walls removed to show the design of the interior thereof; and

This application is a continuation-in-part of the application filed September 14, 1960, under Serial No. D. 62,134, now abandoned.

I claim:

The ornamental design for a bathing unit, as shown and described.
